UNITED STATES PATENT OFFICE.

DAVID KLEIN, OF NEW YORK, N. Y., ASSIGNOR TO MARX FINSTONE, OF BROOKLYN, NEW YORK.

DESIGN FOR A DISPLAY STAND OR SIMILAR ARTICLE.

Application filed July 30, 1923. Serial No. 6,899. Term of patent 7 years.

To all whom it may concern:

Be it known that I, DAVID KLEIN, a citizen of the United States of America, residing at New York city, county and State of New York, have invented a new, original, and ornamental Design for a Display Stand or Similar Article, of which the following is a specification, reference being had to the accompanying drawing, forming part thereof, which represents a perspective view of a display stand employing my new design.

I claim:—

The ornamental design for a display stand or similar article, as shown.

Signed this 18th day of July, 1923, at New York city, N. Y.

DAVID KLEIN.

Witness:

JOHN J. LYNCH.
